CLAIM

The ornamental design for a solenoid tube, as shown and described.

DESCRIPTION

FIG. 1 is a perspective view of a solenoid tube showing our new design;

FIG. 2 is a top view thereof;

FIG. 3 is a bottom view thereof;

FIG. 4 is a front view thereof, wherein a rear view is a mirror image of the front view;

FIG. 5 is a left side view thereof, wherein a right side view is a mirror image of the left view; and,

FIG. 6 is a left side view thereof, showing a solenoid mounted about an exterior surface of the solenoid tube between a coil nut and a hexagon-shaped head of the housing.

The broken lines shown in the figures are for the purpose of illustrating environment and form no part of the claimed design.
